(57) **CLAIM**

The ornamental design for a “home medical instrument,” as shown and described.

DESCRIPTION

FIG. 1 is a perspective view of home medical instrument showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof; and,

FIG. 7 is a bottom view thereof.

The broken lines are included for the purpose of illustrating unclaimed portions of the home medical instrument that form no part of the claimed design.

1 Claim, 7 Drawing Sheets**FIG. 1**

FIG. 2**FIG. 3**

FIG. 4

FIG. 5

FIG. 6

FIG. 7
